[57] CLAIM

The ornamental design for a mobile chair for the handicapped, as shown and described.

DESCRIPTION

FIG. 1 is a side elevational view of the mobile chair for the handicapped, it being understood that the view from the opposite side is a mirror image thereof;

FIG. 2 is a top plan view thereof;

FIG. 3 is a front elevational view thereof;

FIG. 4 is a rear elevational view thereof;

and

FIG. 5 is a bottom plan view thereof.

FIG.1

FIG.2

FIG. 3
